INVENTOR:—

Isadore Bergelson.
BY *Conrad & Peale*,
ATTORNEY.

UNITED STATES PATENT OFFICE

ISADORE BERGELSON, OF PHILADELPHIA, PENNSYLVANIA, ASSIGNOR OF ONE-HALF
TO MORRIS ROSEN, OF PHILADELPHIA, PENNSYLVANIA

SUGAR DISPENSER

Application filed July 21, 1928. Serial No. 294,368.

My invention relates to improvements in dispensers and more particularly to that type used for delivering sugar or similar granular substances and especially designed for table use.

It is an object of my invention to construct a dispenser of this general type in which the container will keep the material or substance sanitary or free from foreign matter and the dispenser will deliver a specific quantity of such material for instance a teaspoonful of sugar, obviating the necessity of using a spoon.

It is a further object of my invention to provide such a device that is simple in construction, easy to take apart, clean, and assemble, and one that can be conveniently operated to deliver the desired quantity of material with certainty.

It is a further object of my invention to so interfit and connect the dispenser device and container that the material will be confined within the container so as to be prevented from entering the housing of the dispenser device or the space between it and that part of the container in which said device is located.

Other objects of my invention will be readily apparent from the following detailed description of my invention taken in connection with the accompanying drawings in which:

Figure 1 is a side elevation, partly in section, showing a dispenser constructed in accordance with my invention;

Fig. 2 is a sectional view showing the dispensing chamber filled and in delivering position;

Fig. 3 is a top elevation; and

Figs. 4 and 5 are details of construction of the mechanism of the dispenser.

Like numerals of references indicate like parts throughout the several views of the drawings.

My improved dispenser comprises a container 1 preferably in the form of a glass jar, and an attachment 2 for dispensing the material from said container and hereinafter referred to as the dispenser in contradistinction to the term dispenser applied to the complete device. The body of the container may be

of any desired shape but provided with a cylindrical neck 3 having external threads and an internal flange or supporting shoulder 4, the latter forming a seat for the cylindrical housing 5 of the dispenser which fits in said neck and is closed at its lower end as shown in Fig. 5. A rubber seal may be employed between the housing and supporting flange or shoulder in the neck of the container, but it is preferred to provide such a close fit that the contents will be prevented from entering the space between the dispenser and neck of the container. Holding the housing in its recess in the neck of the container is a cover plate 6 provided with a downwardly extending peripheral flange threaded to engage the threads of the neck, and passing through central openings in said cover and bottom of the housing to connect the same together is a pin 7 having its ends reduced in diameter to enter said openings and upset or riveted on the parts it connects. Pivoted on this pin within the housing, are two spaced apart disks 8 and 9 connected by a dispensing chamber 10 preferably welded to said disks, the latter being provided with holes on a line with the chamber through which the material passes to and from said chamber. For operating the disks and chamber carried thereby the upper disk 8 at one edge is provided with an operating handle 11 movable in a cut-away portion 5^a of the upper part of the housing and projecting through a slot 6^a in the cover plate beyond which it terminates in a grasping portion 11^a. The slot in the cover plate limits the handle to a swing of 180 degrees representing the two extreme positions of the dispensing chamber, one position registering the chamber with the inlet opening 12 in the closed end of the housing and the other position registering the chamber with the outlet opening 13 in the cover plate, and as it is desired to automatically return the chamber to its closed position with respect to the cover a spring 14 is secured at one end to the housing, as by metal strap 15 welded thereto, and at the other end to a metal strap 16 welded to the dispensing chamber and having an extension 17 curved

around the pivot pin on which the disks are mounted for protecting the spring.

The operation of dispensing the contents of the container in predetermined quantities, determined by the size of the chamber 10, will be readily understood from the foregoing description of the construction of the dispenser device, for parts being in the position shown in Fig. 1 the said chamber is filled by turning the container upside down, and then by moving the handle against the action of the spring so that both ends of the chamber are closed by the disks the container may be turned upright and the handle further turned to bring the chamber in line with the discharge opening in the cover, as shown in Fig. 2 for pouring out the contents of said container. Thus it will be apparent that predetermined qualities of the container may be quickly and easily dispensed by simply turning said container from one position to another and simultaneously manipulating the handle, the spring acting to maintain the upper end of the dispensing chamber closed by the cover so that the contents of the container will be protected and retained in the container in any position of the latter or until the handle of the dispenser device is manipulated in the manner hereinbefore described for the purpose of dispensing a certain quantity of the material according to the size of the chamber. When the dispenser is used for dispensing sugar, for which it is especially adapted, the chamber may be of a size to hold one or two teaspoonfuls of sugar, and as will be obvious my invention may be applied to an ordinary glass fruit jar having an internal shoulder 4, or in connection with a fruit jar without such a shoulder by having an outwardly extending flange 5^b on the housing 5, indicated in dotted lines Fig. 5, whereby the cover or screw cap 6 will securely hold the housing carrying the other parts of the dispensing device securely in the neck of the jar. Other modifications or changes may be made within the spirit and scope of the appended claims.

I claim:

1. A dispenser device for containers comprising a housing fitting within the neck of the container, said housing having a bottom with an inlet opening from the container through the same, a retaining cap fitting over the mouth of the container and having an outlet opening out of line with the aforesaid inlet opening in the bottom of the housing, a pin extending between the cap and bottom of the housing at the center thereof, spaced apart disks rotatably mounted on the pin against the inner sides of the bottom and cap and having a dispenser chamber interposed between them and opening out of each disk, and means for rotating the disks.

2. A dispenser device for containers comprising a housing fitting within the neck of

the container, said housing having a bottom with an inlet opening from the container through the same, a cap fitting on the container and having an outlet opening out of line with the aforesaid inlet opening in the bottom of the housing, a pin connecting the cap and bottom of the housing at the center thereof, spaced apart disks rotatably mounted on the pin against the inner side of the bottom and cap and having a dispenser chamber interposed between them and opening out of each disk, a spring for moving the disks and dispenser chamber to bring the latter in alignment with one of the aforesaid openings, and a handle connected to the upper disk and projecting beyond the container for turning the disks and dispenser chamber against the action of the spring.

3. A dispensing device for containers comprising a two-part housing for the open end of the container one part thereof being a screw cap engaging the container and having a discharge opening therein and the other part having an opening out of line with the aforesaid opening, a pin connecting the two parts of the housing at the center thereof, spaced apart disks located within the housing and rotatable on the pin, a cylindrical chamber forming the dispenser interposed between the disks at one side of the pin, said chamber opening out through the disks, a handle extending from one of the disks through a slot in the aforesaid screw cap for rotating the disks and dispensing chamber with respect to the opening in the housing, and a spring connected to the chamber and to the housing for moving said chamber normally in alignment with one of the openings in the housing.

4. A dispensing device for containers comprising a two-part housing for the open end of the container one part thereof being a screw cap engaging the container and having a discharge opening therein and the other part having an opening out of line with the aforesaid opening, a pin connecting the two parts of the housing at the center thereof, spaced apart disks located within the housing and rotatable on the pin, a cylindrical chamber forming the dispenser interposed between the disks at one side of the pin, said chamber opening out through the disks, and a handle extending from one of the disks through a slot in the aforesaid screw cap for rotating the disks and dispensing chamber with respect to the opening in the housing; together with a metal strap welded to one side of the housing, a metal strap welded to the chamber and having an extension around the pin, and a helical spring connected at its ends to said straps for moving the dispensing chamber normally in line with the opening in the bottom of the housing with the upper disk closing the opening in the screw cap.
